UNITED STATES PATENT OFFICE.

WILLIAM H. TEELING, OF PITTSFIELD, MASSACHUSETTS.

IMPROVEMENT IN HEATING-STOVES.

Specification forming part of Letters Patent No. 148,779, dated March 17, 1874; application filed February 17, 1873.

To all whom it may concern:

Be it known that I, WILLIAM H. TEELING, of Pittsfield, in the county of Berkshire and State of Massachusetts, have invented an Improved Heater, of which the following is a specification:

Figure 1 is a vertical central section of my improved heater, the line *c c*, Fig. 2, indicating the plane of section. Fig. 2 is a horizontal section of the same, taken on the plane of the line *K K*, Fig. 1.

Similar letters of reference indicate corresponding parts.

This invention has for its object to utilize, to the fullest extent, the heating capacity of a stove or furnace for raising the temperature of the air which circulates through and surrounds it; and my invention is designed as an improvement upon that class of heaters in which is employed an air-heating chamber, composed of an upper and lower cylinder, connected by air-flues, through which passes heated air, said cylinders and pipes being arranged above the fire-chamber, to cause the heated products of combustion to pass through said chamber and pipes. My invention consists in interposing a series of smoke-flues and air-space between two plates, one of which covers the fire-space, while the other forms the bottom of a hot-air chamber, containing a series of open-ended air-tubes, whereby two compartments for heating the air are secured, viz., one in which the air surrounds the smoke-flues, while in the other the smoke surrounds the air-flues, so that in both a large heating-surface is utilized.

In the accompanying drawing, the letter *A* represents the fire-grate of my improved stove or furnace. *B* is the fire-chamber over the grate. *C* is a plate covering the fire-space and supporting a series of open-ended pipes, *D D*, of suitable length, through which the pro-

ducts of combustion pass upward into a chamber, *E*. The bottom *F* of this chamber *E* coincides with the upper ends of the pipes *D D*, while the smoke-flue *G* projects from its upper part. *J J* are a series of open-ended tubes, extending from top to bottom of the chamber *E*.

The air surrounding and heated by the outer sides of the pipes *D* ascends in the tubes *J*, and is therein further heated by the gases of combustion, which surround said tubes during their passage through the chamber *E*. Thus there are two compartments for heating the air, one, *H*, in which the air surrounds the smoke-flues *D*, and the other, *E*, in which the smoke surrounds the air-flues *J*, and, in both compartments a large amount of heating-surface is utilized for transmitting the heat of the gases of combustion to the air.

L is a case or shell embracing the entire apparatus, constituting, if desired, the side of the chamber *E*, and embracing, also, the lower air-chamber *H* and the fire-chamber. The top of this shell, if used, is perforated to permit the escape of the heated air, in the manner indicated; or else a hot-air flue may be placed over the chamber *E*, to conduct the heated air to other apartments or stoves.

I claim—

The described combination, in a stove or furnace, of the horizontal air-space *H* and vertical air-pipes *J*, with the smoke-flues *D*, smoke-chamber *E*, fire-space *B*, and perforated bottom *I*, the air entering at the bottom being heated by contact with the walls of the fire-chamber in its passage to the air-space *H*, substantially as and for the purpose specified.

W. H. TEELING.
